DESIGN FOR A BABY'S WALKER OR SIMILAR ARTICLE

Leslie Peltier, Delphos, Ohio

Application June 4, 1943, Serial No. 110,365

Term of patent 3½ years

(Cl. D15—1)

To all whom it may concern:

Be it known that I, Leslie Peltier, a citizen of the United States, residing at Delphos, in the counties of Allen and Van Wert, State of Ohio, have invented a new, original, and ornamental Design for a Baby's Walker or Similar Article, of which the following is a specification, reference being had to the accompanying drawing, forming a part thereof.

Fig. 1 is a perspective view of a baby's walker or similar article, showing my new design; and Fig. 2 is a top plan view thereof.

I claim:

The ornamental design for a baby's walker or similar article, as shown.

LESLIE PELTIER.
